CLAIM

The ornamental design for a roller catalog case, as shown and described.

DESCRIPTION

FIG. 1 is a front elevational view of a roller catalog case showing my new design with the extendable handle in the partially covered retracted position;

FIG. 2 is a top plan view thereof;

FIG. 3 is a bottom plan view thereof;

FIG. 4 is a rear elevational view thereof;

FIG. 5 is a left side elevational view thereof;
FIG. 6 is a front elevational view thereof with the handle extended; and

FIG. 7 is a right side elevational view of FIG. 6 in a slightly tilted position for rolling.

FIG. 1

FIG. 2

FIG. 3

FIG. 4

FIG. 5
